UNITED STATES PATENT OFFICE.

JEAN ERNEST SONNIER, OF PARIS, FRANCE.

METHOD OF MANUFACTURING METALLIC TORSELS.

1,104,714.

Specification of Letters Patent. Patented July 21, 1914.

Application filed November 24, 1913. Serial No. 802,720.

To all whom it may concern:

Be it known that I, JEAN ERNEST SONNIER, a citizen of the Republic of France, and a resident of 4 Boulevard Diderot, Paris, France, have invented new and useful Improvements in Methods of Manufacturing Metallic Torsels, of which the following is a specification.

The present invention pertains to a process of manufacture of metallic torsels or twisted or wreathed columns, pillars or the like with any number of strands made from sheets of metal.

The process consists in rolling the edges of the rectangular sheet metal in the direction of its length so as to form marginal tubes leaving between them a middle strip—more or less wide—of undeformed metal, in folding or shaping the middle strip according to any desired number (zero being included) of undulations, in afterward bringing together both the marginal tubes in such a way as to squeeze the undulations of the middle strip, and lastly in imparting to the whole a twisting movement around the longitudinal axis of the sheet. When the number of undulations of the middle strip is even or *nil*, the marginal tubes must be rolled one on the one face and the other on the other face of the sheet. On the other hand, when the number of the undulations of the middle strip is an odd number, the marginal tubes must be rolled on the same face of the sheet.

The annexed drawing shows by way of example, various forms of carrying out the invention.

Figures 1 to 4 show two steps in the manufacture of a torsel or twisted column with two strands. Figs. 1 and 3 are views in elevation. Fig. 2 is a cross section of Fig. 1; Fig. 4 is a cross section of Fig. 3. Figs. 5 to 7 show stages in the manufacture of a three strand torsel or wreathed column. Figs. 5 and 6 are cross sections. Fig. 7 is an elevation. Figs. 8 to 10 show the steps in the manufacture of a four-strand torsel or wreathed column. Figs. 8 and 9 are cross sections and Fig. 10 is an elevation. Figs. 11 and 12 are cross sections showing two steps in the manufacture of a five-strand torsel or wreathed column. Figs. 13 and 14 are transverse sections showing two steps in the making of a six-strand torsel or wreathed column. Figs. 15 and 16 are transverse sections showing a modification in the

manner of making four-strand torsels or wreathed columns.

In order to make a two-strand torsel or wreathed column, I take a rectangular sheet of metal of which I roll the longitudinal edges in such a way as to form two marginal tubes *a* situated one on one face, the other on the other face of the sheet (Figs. 1 and 2). Between the two tubes *a* there remains an undeformed strip of metal *b*. There is afterward imparted to the whole a twisting movement around the longitudinal axis of the sheet which action gives the two-stranded torsel or wreathed column shown in Figs. 3 and 4. The presence of the strip *b* enables the twisting to take place without deforming in any way the tubes *a*; the appearance of the torsel or wreathed column is as bold as the strip *b* is wide. It will be seen that the two-strand torsel or wreathed column corresponds to the number zero of undulations of the middle strip *b*.

In order to make a three-strand torsel or wreathed column, I first roll the edges of the sheet on the same face of the sheet and arrange between the two marginal tubes *a*, a strip *b* of which the width is slightly greater than the full circumference of a tube *a*. I shape the strip *b* in such a way as to form one undulation *b'* (Fig. 5) and then bring together the tubes *a* so as to close in or crush the base of the undulation *b'* (Fig. 6). It is then sufficient to impart to the whole a twisting movement about its longitudinal axis, in order to obtain the three-strand torsel or wreathed column shown in Fig. 7.

To make a four-strand torsel or twisted column, the tubes *a* are rolled on opposite faces of the sheet: the middle strip *b* is folded into two undulations *b'* *b''* (Fig. 8) the tubes *a* are brought together (Fig. 9) and the twisting action is applied to the whole around its longitudinal axis. In this way the four-stranded torsel or wreathed column is obtained which is shown in Fig. 10.

Figs. 11 and 12 show the manner of making a torsel or wreathed column having five strands (three undulations *b'* *b''* *b'''*), and Figs. 13 and 14 show the manner of constructing a six-strand torsel or wreathed column (four undulations *b'* *b''* *b'''* *b''''*). It will be seen that the method is general in its application.

Figs. 15 and 16 illustrate a modified way of constituting the torsel or wreathed pillar with four strands. I take two sheets of

metal A B and A' B' prepared as for the two-strand torsels; these two sheets are assembled by means of a double hook A² B² composed of a metal sheet prepared in the 5 same way as the sheets A B and A' B' but of which the marginal tubes are of larger diameter (Fig. 15). The whole is afterward subjected to a twisting process around the longitudinal axis. In this way a torsel or 10 twisted column is obtained of which the section is shown in Fig. 16 and of which the external appearance corresponds with that of Fig. 10. This modified method enables me to employ metal sheets of different 15 appearance, that is to say, to vary the decorative and artistic effect obtained.

Torsels or twisted or wreathed columns constructed according to this invention possess, together with a decorative appearance, 20 a rigidity and a resistance of quite a remarkable character. They behave almost the same as profiled metal, angle iron and the like and can sustain and support considerable loads in the longitudinal direction 25 by reason of the connection or tie which exists for the whole length of the strands.

What I claim and desire to secure by Letters Patent of the United States is:

1. A method of constructing torsels from 30 sheet metal, which comprises rolling the longitudinal edges of a sheet metal blank into

marginal tubes spaced apart by an undeformed portion of the blank, and twisting the blank about its longitudinal axis, substantially as described.

2. A method of constructing torsels from sheet metal, which comprises rolling the longitudinal edges of a sheet metal blank into marginal tubes spaced apart by an undeformed portion of the blank, undulating the latter portion of the blank, pressing the tubular margins together to close in the base of the undulation and twisting the blank about its longitudinal axis, substantially as described.

3. A method of constructing torsels from sheet metal which comprises rolling the longitudinal edges of a sheet metal blank into marginal tubes spaced apart by an undeformed portion of the blank, imparting a plurality of undulations to the latter portion, pressing the tubular margins together to close in the bases of the undulations and twisting the blank about its longitudinal axis.

In testimony whereof I have signed my name to this specification, in the presence of two subscribing witnesses.

JEAN ERNEST SONNIER.
